UNITED STATES PATENT OFFICE.

HARRY F. SMITH, OF DAYTON, OHIO, ASSIGNOR TO THE GAS RESEARCH COMPANY, OF DAYTON, OHIO, A CORPORATION OF OHIO.

FURNACE.

Application filed April 22, 1925. Serial No. 25,154.

This invention relates to heat-transferring devices, and more particularly to furnaces or ovens such as are used for heat treating, enameling, and the like.

5 One of the principal objects of the invention is to provide apparatus of this character, for utilizing a combustible fuel such as oil, gas, or the like, which is so constructed and arranged that the products of combustion 10 resulting from the burning of the fuel do not enter the work-receiving chamber, so that any desired atmosphere may be maintained within the work-receiving chamber; while at the same time high thermal efficiency is attained.

15 Another object of the invention is to provide apparatus of this character in which the heat generated by the burning of the fuel is transferred to a refractory member which in 20 turn transfers the received heat, primarily, by radiation, to the work within the work-receiving chamber.

Other objects and advantages of the invention will be apparent from the description 25 thereof set out below when taken in connection with the accompanying drawing.

In the drawing in which like characters of reference designate like parts throughout the several views thereof—

30 Fig. 1 is a plan view of a heating furnace constructed in accordance with this invention;

Fig. 2 is a vertical sectional view along the line 2—2 of Fig. 1;

35 Fig. 3 is a vertical sectional view along the line 3—3 of Fig. 2;

Fig. 4 is a detail sectional view through the recuperator manifold; and one of the recuperator tubes;

40 Fig. 5 is an enlarged detail view of the manifold construction;

Figs. 6, 7, 8, 9 and 10 are cross sectional views through somewhat modified forms of recuperator tubes;

45 Fig. 11 is a vertical sectional view through a furnace provided with a plurality of refractory elements, in lieu of the large refractory element housing the work-receiving chamber as shown particularly in Figs. 2 and 3;

50 Fig. 12 is a plan view, with parts broken away and shown in section, of the construction shown in Fig. 11;

Fig. 13 is a fragmentary sectional view of

a slightly modified form of furnace construction; and

Fig. 14 is a plan view of the door construction and mounting.

Furnaces adapted to operate upon combustible fuel such as oil, gas, coal, and the like, as heretofore used have been objectionable for two general reasons;—first, that where the fuel burned, and the resulting hot products of combustion are brought through the work-receiving chamber adequate control of the atmosphere within the work-receiving chamber can not be secured; and second, where a muffle type furnace is provided in which the hot products of combustion do not pass through the work-receiving chamber, either efficiency of the furnace is low or the furnace has failed to stand up in operation. This invention avoids both of these broad grounds of objection, and provides a furnace in which the atmosphere within the work-receiving chamber may be just as readily controlled as may be done with an electric furnace, and yet a very high degree of efficiency may be secured, efficiencies quite as high as any secured with other known forms of furnaces, electric or otherwise.

As illustrating a preferred embodiment of the invention, and by way of description, the invention is herein shown as applied to a type of furnace particularly designed for use in brazing or soldering copper fins upon an iron or steel cylinder for use in air cooled gas engines, such for instances as the well known Delco-Light engine. And for this particular brazing or soldering operation the work within the work-receiving chamber is heated to a temperature of about 1850° F.

In the form of furnace shown particularly in Figs. 1—4, the furnace comprises the usual metallic shell 20 provided with brick work within which is arranged a substantially circular combustion space 21, a layer of suitable refractory material 22 forming the effective wall of this combustion space. A gas and fuel inlet orifice 23 is connected to the combustion space, and a gas outlet passage or orifice 24 is also connected thereto, the inlet and outlet orifices, as shown particularly in Fig. 3, being located adjacent each other and separated by means of a wall 25, so that the incoming fuel and products of combustion pass completely

around the combustion chamber and out through the outlet orifice 24. The outlet orifice in turn is connected to a flue or passage 26, which opens into the vent or stack 27. The inlet orifice is preferably substantially tangential to the combustion space.

Positioned within the combustion space, and spaced from the walls thereof is a refractory cylinder 30, which may be made of any suitable material, such as refractory earth work, or some of the commercially known highly heat resistant nickel chromium alloys. As is clearly shown in Fig. 2 this refractory cylinder or wall 30 has its ends suitably mounted or imbedded in the lining, the work-receiving chamber 31 within this element 30 being thus completely separated from the combustion space so that none of the products of combustion within the combustion space can pass into the work-receiving chamber. As a consequence the atmosphere within the work-receiving chamber may be controlled as desired, just as readily as is the case with an electric furnace. The refractory element 30 is preferably made as thin as consistent with safety and long life. In a furnace used in the manufacture of copper fin cylinders, as referred to above, the refractory metallic element 30 was constructed to give a work-receiving chamber approximately 27 inches in diameter, the wall of this element being about one half to three quarters of an inch thick.

As stated the air and fuel forming the combustible mixture are introduced through the passage 23 and the hot products of combustion resulting from the burning of this mixture pass completely around the refractory wall 30. As shown in the drawing, particularly in Figs. 2 and 3, the wall 25 is so arranged that the combustion space 21 is oppositely tapered, its maximum width being at approximately the point of contact 45 of the wall 25 with the surface of the refractory element 30. This combustion space 21 has a progressively increasing width from the fuel inlet reaching a maximum at substantially the point of contact of the wall 50 25 with the refractory element 30, and having a progressively decreasing width from then on around the refractory element to the outlet end. As a result substantially uniform velocity of flow of the burning 55 gases, and the resulting products of combustion, through the combustion space is secured. As they thus pass around through the combustion space they heat the refractory wall 30, and the opposed surface of 60 the layer of refractory material 22, by convection, as the hot products of combustion wipe over the respective surfaces of these members at considerable velocity. In addition, especially at high temperatures, there 65 will be a very considerable transfer of heat

from the surface of the heat resisting lining 22 to the refractory element 30 by radiation, so that the refractory element 30 will be heated to a high temperature, well above the temperature of incandescence in the embodiment of the invention shown.

The heat received by the refractory member 30 is transferred in turn to the work within the work-receiving chamber inside this refractory member primarily by radiation. Of course the atmosphere within the refractory cylinder 30 will receive some heat by convection from the refractory element as this atmosphere is free to circulate therein, but the heating of the work within the work-receiving chamber will be accomplished primarily by the transfer of radiant energy from the incandescent refractory member 30 to the work. And inasmuch as the tendency for a heated body to radiate heat energy varies as the fourth power of the temperature of that body, it is evident that a very efficient transfer of the heat energy from the member 30 into the work will be secured.

As the heated products of combustion pass through the combustion space and around the refractory element there is, of course, a temperature drop—the incoming gases being hotter than the off-going gases. Consequently there is a tendency toward uneven heating of the refractory element, with resulting uneven distribution of heat energy to the work within the work chamber. In order to overcome this tendency to uneven heating a series of plates or screens 32 are arranged within the combustion space, in the path of the flowing heated products of combustion; these plates picking up the heat energy from the heated gases and in turn radiating such received heat energy to the refractory element 30. And by progressively increasing the number of these plates so that as the temperature of the products of combustion falls the number of plates is increased, the heat input into the member 30 may be maintained substantially uniform throughout. For a greater number of plates under a decreased temperature differential will absorb as much heat as a smaller number of plates under a greater differential. As shown in Figs. 1 and 2 no plates are positioned within the inlet end of the combustion space where the temperature is highest. Some plates are positioned beginning about half way round, and an additional number adjacent the outlet opening.

In order to still further increase the efficiency of the furnace, the air, or the fuel, or both, are preheated. As shown in Figs. 1, 2 and 3 the furnace is arranged to operate upon gas, such as producer gas, as a fuel, and the construction is such that both the air and the gas are preheated. As a matter of fact the furnace referred to above for

the manufacture of copper finned cylinders has been operated very satisfactorily with preheating of both the air and the gas, and also with the preheating of the air alone. 5 Where both air and gas are preheated the efficiency is greater than where only the air alone is preheated.

For accomplishing this preheating of the air recuperator tubes are positioned within 10 the passage 26, where they are subjected within the path of travel of the heated products of combustion passing from the outlet orifice 24 to the vent or stack 27. Where both air and gas are to be preheated a divided manifold 40 is provided, the construction of which is shown most clearly in Figs. 1 and 4. This divided manifold has a partition 41 dividing it into two passages 42 and 43. One of these passages 42 is connected to a supply of air under suitable pressure, while the other 43 is connected to a supply of 20 gas, or other suitable combustible fluid. A plurality of recuperator tubes 45 are provided, each of which has a down turned end 46, constructed for tight connection with the upper surface of the manifold, as shown particularly in Fig. 4. Any desired means for securing the tight connection may be used, but preferably the down turned end 30 of the recuperator tube and the surface of the manifold are both machined so that a tight metal to metal joint may be had. To hold the various recuperator tubes tightly positioned with respect to the manifold, each 35 tube is provided with a tapered outstanding flange 47, surrounding its down turned end. The manifold is provided with a plurality of openings 48 each of which is adapted to register with the passage within a cooperating recuperator tube; and adjacent each of 40 these openings 48 the manifold is provided with two upstanding lugs 49 and 50. The lug 49 is provided with an overhanging portion 51, which is shaped to cooperate 45 with the tapered flange 47. The lug 50, upon the opposite side of the manifold, carries a threaded bolt 52 therein, the construction being such that the end of this bolt may be brought against the cooperating tapered flange 47 upon the recuperator tube, forward movement of this bolt resulting in a wedging of the inclined faces of the flanges 47 between the overhanging portion 51 of the lug 49 and the bolt 52, whereby tight 55 contact of the machined surfaces of the over-turned end of the recuperator tube and of the upper face of the manifold surrounding the opening 48 is secured.

As is shown by Figs. 4 and 5 the partition 60 41 of the divided manifold is so arranged that the openings 48 in the upper wall of the manifold are connected alternately to the passages 42 and 43, so that these openings 48 are alternately connected to the air supply and to the fuel supply. And when

the recuperator tubes are positioned in place, these tubes will be connected alternately to the air supply and the fuel supply. The discharge ends of the recuperator tubes, as will be seen in Fig. 3, are located within the 70 dividing wall 25 so that the air and the fuel discharged from these tubes pass into the inlet passage 23 where they mix and burn, the hot products of combustion passing around through the combustion space 22. A 75 suitable removable hollow plug 55 is positioned in the outer end of the passage 23, which plug has a swinging cover plate by means of which access to the passage 23 may be had to ignite the mixture of air and 80 fuel.

Preferably the recuperator tubes have positioned within them means for causing the transfer of heat energy from the tubes to the air and gass passing therethrough at a 85 rate in excess of that which would normally be attendant upon the transfer of heat from these tubes by convection into the air or fuel passing through them.

In Figs. 6, 7 and 8 are shown three constructions whereby in a recuperator tube which is rectangular in cross section, as are the tubes shown in Figs. 1-4, this increased heat transfer may be secured. The tube has positioned therein as shown in Fig. 6, for 90 example, a plurality of layers of wire screen, which should be of some suitable material, such for example, as nickel chromium alloy, or any other material of a nature adapted to stand up under the temperatures attained 95 by it. The hot products of combustion passing through the passage 26 will heat the recuperator tubes to incandescence and the heat energy received by these tubes will be transferred by radiation to the screens 100 shown in Fig. 6. Because of the very rapid increase in the rate of transfer of heat energy by radiation with increases in 105 temperature, the rate of transfer where the temperature of the tube is above the temperature of incandescence will be extremely rapid so that the screens will receive radiant energy in large quantities. Furthermore these screens because of their construction tend to break the flowing currents of air or 110 fuel into very finely divided streams so that an extremely intimate contact is secured as between the flowing fluid and the surfaces of heated screens. As a result the transfer by 115 means of convection from these screens to the flowing fluid is very much more rapid, and much greater in amount, than is the transfer from the wall of the recuperator tube direct to the flowing fluid. Thus the 120 temperature of the screens is maintained 125 comparatively quite low even though large quantities of heat are radiated from the recuperator tube to these screens. As a result of this large temperature drop the tube itself is enabled to receive considerably greater 130

quantities of heat by convection from the hot products of combustion passing over the outside. And as a consequence a large proportion of the heat contained in the hot products of combustion when they escape from the combustion space 22 through the outlet orifice 24 is removed, so that the heat loss in the products of combustion passing through the vent or stack 27 is comparatively quite low; that is the thermal efficiency of the furnace is quite high.

The heat imparted to the fluid flowing through the recuperator tubes of course goes toward the setting up of higher combustion temperatures within the combustion space 22, and this in turn increases the rate of transfer of heat to the work within the work-receiving chamber.

In Fig. 7 is shown a somewhat different arrangement of the screens within the recuperator tubes. It might happen that the mesh in the screens would tend to match so that the screens will pack and so adequate passages for the movement of the air or other fluid through the recuperator tube will not be present. In such case the desired intimate contact of the flowing fluid and the screens would not be secured. In the form shown in Fig. 7 the screens before they are inserted within the recuperator tube are stamped or dimpled to provide projections 65, which tend to space the screens adequately and prevent this packing. In the form shown in Fig. 7, as well as in the form shown in Fig. 6 a partition 62 is provided. It has been found that the penetrating power of the energy radiations from the recuperator tube is limited because of the interference of the strands or wires of the screen, and where more than two or three layers of screen are used the remaining layers not only do not tend to add to the efficiency of the device, but actually decrease its efficiency, since they merely permit a passage through which the gases may flow without being brought into contact with the heated metal. As a consequence the recuperator tubes are divided by partitions and the layers of screen are so arranged that not only will the energy radiations heat up the several screens on each side of the partition but they will also heat the partition itself so that the efficiency of the transfer within the tubes by means of convection is very greatly increased.

In Fig. 8 is shown a different form of recuperator tube in which the tube is filled with a plurality of smaller tubes to split the flowing fluid into streams of small diameter and to effect intimacy of contact between the heated metal and the flowing fluid.

In Figs. 9 and 10 the recuperator tube is shown as of cylindrical shape instead of rectangular shape as is true in the previous figures. In Fig. 9 the tube comprises the

spaced cylindrical walls 70 and 71 which have positioned between them the screens or perforated parts 72. The operation is the same as with the forms described above. In Fig. 10 the tube is also formed by spaced walls 73 and 74, between which are positioned small tubes 75, which serve the same purpose as the small tubes shown in Fig. 8.

As described above the furnace has the usual construction of brick, with the combustion space provided with a lining of refractory material, such as fire clay, or fire brick. The rear end of the work-receiving chamber, within the cylindrical refractory member 22, is closed by means of suitable refractory material, and the front end is also so closed. The front end of the work-receiving chamber is provided with an opening 100 adapted to receive a door 101, the body of the door being composed of suitable refractory material, mounted upon a metal plate 102. This metal plate 102 carries a pair of lugs 103, which are arranged along substantially the vertical diameter of the door. Positioned within these lugs and pinned thereto is a vertical shaft 104, the arrangement being such that the shaft and the door move together. The upper and lower ends of this shaft are rotatably mounted respectively in two aligned passages within the free ends of two links 105 the other ends of which are rigidly mounted upon the shaft 106 which is in turn rotatably supported in standard 107 carried by the shell of the furnace. Rigidly carried upon the shell of the furnace, adjacent the upper standards 107 is an additional standard 108, which has pivotally attached thereto a link 109, the free end of which is connected by means of a second link 110 to the door through the medium of the shaft 104, the link 110 being fixed upon the upper end of the shaft 104.

The links 109 and 105 are so arranged that as the door swings open the path of travel 110 of the free ends of the two links will intersect. As a result of this construction as the door swings open it will move through such path that its inner face, the face which is presented to the interior of the work-receiving chamber and is therefore at extremely high temperature during operation, will at all times face toward the furnace, so that the likelihood of injury to the operator as a result of coming in contact with the hot face of the door or as a result of heat energy radiated from the door, will be minimized.

The upper end of this rotatable shaft 106 carries thereon a sheave or sprocket wheel 115, adapted to receive an operating chain 125 the two ends of which pass backwardly over the top of the furnace, one of these ends passing over a sheave or sprocket wheel 116 and thence downwardly around an operating drum 117 to which is connected an op-

erating motor 118, the other end passing over a similar sheave or sprocket 120, and having a counter-balance weight 121 hung on the free end thereof. Any suitable control switch, illustrated diagrammatically at 122 may be included in the motor circuit 123. When it is desired to open the door the motor 118 is actuated to cause rotation of the wheel 115, which acting through the shaft 106 and the links 105 pinned thereto swings the door outwardly upon these links. But because of the inter-connection of the links the path of travel of the door is controlled as set out above.

When the door of a furnace as ordinarily constructed is open the furnace tends to cool down partly because of the possible ingress of cold air, partly because of the insertion of cold work to be heated up, and also because of the very high rate of heat loss from the heated material of the door and the inlet within which the door sets. Where copper fins are to be brazed to a cylinder, as referred to above, the walls of the work chamber are at a temperature of approximately 1850° F. when the furnace is closed and operating at normal temperature. Naturally at this high temperature the heat losses, when the door is opened, from heated surfaces exposed to the outside would be extremely high. In order to cut down these heat losses the face of the door is covered with a comparatively thin layer of some heat insulating material 135 such as fibrous asbestos or the like, and over this is arranged a layer of wire screen, or the like, 136 preferably of some metal such as nickel chromium alloy which is highly resistant to oxidation at high temperature. This screen serves primarily to hold the fibrous asbestos in position. The thickness of the layer of asbestos may be varied as desired but it should preferably be of small heat capacity so that even if cooled down only a comparatively small heat loss will result. And as a result of this construction the heat losses are very materially cut down. In actual operation when the interior of the material of the door is at white heat with the door open, the screen and the layers of asbestos may be cooled to such a low temperature as to be not incandescent; the high resistance to transfer of heat from the body of the door through the asbestos preventing substantial cooling of the main body of the door. Not only does the layer of heat insulating material thus cut down heat losses; but in addition the door is so arranged and mounted that when in closed position in the inlet to the work chamber it substantially fills the inlet, with its inner face nearly flush with the inner wall of the work chamber. This tends to prevent heating of the side wall of the door and of the wall of the inlet passage so that these parts are of much lower

temperature than the inside of the work chamber, generally well below incandescence and consequently the heat lost when the door is open both by radiation from the wall of the inlet and by direct contact with the air is much less than with the usual construction.

In addition the door and the wall of the inlet passage to the work chamber are made of varying diameter, being given a stepped down construction as shown by the numeral 137 to provide a plurality of ledges or walls which interrupt the transfer of radiant energy from inside the work chamber through the space between the door and the wall of the inlet opening.

By means of these several constructions the heat losses when the door is opened are very materially reduced, consequently the furnace comes up to temperature more quickly after it is charged, and greater efficiency is thus secured together with a greater work output.

In Figs. 11 and 12 is shown a somewhat modified form of furnace construction. In the form of furnace described above the work is received within a refractory member 30, the hot products of combustion passing around the outside of this refractory member. This construction of course is not essential, and the character of the work-receiving chamber, and the form and position of the refractory radiating elements may be varied as desired, and to accord with the character of the work to be handled.

In Figs. 11 and 12, for example, the single refractory member 30 is dispensed with and in lieu thereof a plurality of small refractory members are provided, which extend through a work-receiving chamber 150, formed in any conventional manner within a suitable furnace construction, this construction being illustrated generally as comprising a metallic shell 151 and suitable refractory or heat resisting lining 152. The hot products of combustion may be introduced in any desired way to the refractory elements 153. As shown each refractory element or tube 153 is provided with a suitable burner 154, through which air and a suitable fuel are introduced for burning within the refractory tube itself. Each of the tubes is shown as provided with its own burner element, but of course this construction is not necessary. A single burner element may be provided for a manifold, or combustion space, the hot products of combustion passing from such combustion space into the refractory tubes. Also the form of the recuperator elements is not shown in Figs. 11 and 12, but it is to be understood that preheating of the air, the fuel, or both, may be accomplished in the manner described above.

The hot products of combustion passing

through the refractory tubes heat those tubes, and the heat energy received by them is radiated to the work within the work-receiving chamber 150, and also to the walls 5 of that chamber. As shown the upper wall of the chamber is so shaped that the heat received thereby is in turn radiated downwardly toward the work within the chamber. As a result high efficiency is secured.

10 In order to effect proper transfer of the heat energy from the products of combustion to the refractory tubes, means is preferably provided within these tubes to give an increased transfer of heat over that which 15 would normally result from convection as the products of combustion sweep over the inner walls of the tubes. These means consist of screens or perforated plates 160 such as are described above in connection with the 20 recuperator tubes, these plates picking up the heat from the hot products of combustion as those products pass over and through the screens, the heated screens then in turn radiating the received heat to the refractory 25 tubes to heat those tubes; the transfer of the heat energy being thus just the reverse of the transfer in the recuperator tubes.

In order to maintain a uniform temperature throughout the work-receiving chamber 30 150, especially where that chamber is of considerable size, it is preferable to so locate the screens 160 that the refractory tubes will be uniformly heated throughout their length despite the fact that the products of combustion 35 are of progressively decreasing temperature as they pass through the tubes, due to the giving up of heat to the tubes. The desired arrangement of these elements is shown in Fig. 12, wherein no screens or perforated plates are provided in the extreme 40 end of the tube where the combustible mixture is burned or enters and the number of screens is progressively increased from that end of the tube to the outlet end. As a result 45 as the temperature tends to fall the number of screens is increased so that even though the temperature differential between the increased number of screens and the products of combustion is less nevertheless 50 the number of screens being greater the actual amount of heat energy received by the increased number of screens will be substantially the same as the amount received by a lesser number of screens but under a 55 higher temperature differential. By means of this construction not only is the transfer of heat to the refractory elements made more efficient, but also a more uniform distribution of heat is secured.

60 In Fig. 13 is shown a slightly modified form of construction in which only the air is preheated. A divided manifold is not needed here so a single manifold 170 is provided to which are connected in the manner described above recuperator tubes which de-

liver heated air into the inlet passage 23 of the combustion space. The gas, or other fuel, is introduced through a suitable burner element 171 into the inlet of the combustion space to mingle with the incoming air and burn therewith. It has been found that with this construction a somewhat more uniform temperature distribution may be at times secured, but at the expense of efficiency, than where there is recuperation both 75 as to air and fuel.

While the forms of apparatus herein disclosed constitute preferred embodiments of the invention, it is to be understood that the invention is not limited to these precise 80 forms of apparatus, and that changes may be made therein without departing from the scope of the invention which is defined in the appended claims.

What is claimed is:

1. A furnace for operating upon combustible fuels comprising a combustion space, a refractory wall within said combustion space defining and enclosing a work-receiving chamber the construction being such that products of the combustion within the combustion space will not enter the work-receiving chamber, and means positioned within the combustion space and out of substantial heat conducting contact with the said refractory wall for receiving heat energy from the burning of the fuel within the combustion space and for transferring such heat energy primarily by radiation into the said refractory wall.

2. Heat transferring apparatus of the character described for operating upon combustible fuels, comprising a work-receiving chamber, a combustion space separate from said work-receiving chamber whereby products of combustion of the fuel will not enter the work chamber, and means positioned out of substantial heat conducting contact for receiving heat energy from the burning of the fuel within the combustion space and for transferring such heat energy primarily by radiation into the work inside the work-receiving chamber.

3. Heat transferring apparatus of the character described adapted to operate upon combustible fuel comprising a combustion space, a refractory wall separating said combustion space from a work-receiving chamber, the construction being such that products of the combustion within the combustion space will not enter the work-receiving chamber, said refractory wall being positioned and constructed to receive heat energy on one side thereof from the products of combustion and transfer said heat energy from the other side thereof into the work chamber, primarily by radiation, and members associated with the refractory wall constructed for receiving heat energy by convection from the products of combustion and for transferring

such received heat energy to the refractory wall, said members being arranged in progressively increasing numbers as the temperature of the products of combustion decreases.

4. A furnace of the character described, adapted to operate upon combustible fuels, having a circular chamber therein, a refractory element positioned within said circular chamber and dividing said chamber into a work-receiving chamber and a surrounding combustion space, the said refractory element so separating the work-receiving chamber and the combustion space as to prevent products of combustion passing from the combustion space into the work-receiving chamber, a fuel inlet passage within the furnace wall opening into the combustion space and a fuel outlet passage within the furnace wall connected to the combustion space, the said inlet and outlet passages being arranged in juxtaposition, whereby the products of combustion within the combustion space are caused to travel completely around the refractory wall enclosing the work-receiving chamber.

5. A furnace of the character described, adapted to operate upon combustible fuels, having a circular chamber therein, a refractory element positioned within said circular chamber and dividing said chamber into a work-receiving chamber and a surrounding combustion space, the said refractory element so separating the work-receiving chamber and the combustion space as to prevent products of combustion passing from the combustion space into the work-receiving chamber, a fuel inlet passage within the furnace wall opening into the combustion space and a fuel outlet passage within the furnace wall connected to the combustion space, the said inlet and outlet passages being arranged in juxtaposition, whereby the products of combustion within the combustion space are caused to travel completely around the refractory wall enclosing the work-receiving chamber, and recuperator tubes within the said outlet passage.

6. A furnace of the character described, adapted to operate upon combustible fuels, having a circular chamber therein, a refractory element positioned within said circular chamber and dividing said chamber into a work-receiving chamber and a surrounding combustion space, the said refractory element so separating the work-receiving chamber and the combustion space as to prevent products of combustion passing from the combustion space into the work-receiving chamber, a fuel inlet passage within the furnace wall opening into the combustion space and a fuel outlet passage within the furnace wall connected to the combustion space, the said inlet and outlet passages being arranged in juxtaposition, whereby the

products of combustion within the combustion space are caused to travel completely around the refractory wall enclosing the work-receiving chamber, and a recuperator tube located within said outlet passage, one end of said tube being connected to a source of supply of one of the constituents of the combustion, and the other end opening into the said fuel inlet passage.

7. A furnace of the character described, adapted to operate upon combustible fuels, having a circular chamber therein, a refractory element positioned within said circular chamber and dividing said chamber into a work-receiving chamber and a surrounding combustion space, the said refractory element so separating the work-receiving chamber and the combustion space as to prevent products of combustion passing from the combustion space into the work-receiving chamber, a fuel inlet passage within the furnace wall opening into the combustion space and a fuel outlet passage within the furnace wall connected to the combustion space, the said inlet and outlet passages being arranged in juxtaposition, whereby the products of combustion within the combustion space are caused to travel completely around the refractory wall enclosing the work-receiving chamber, and a recuperator tube located within said outlet passage, one end of said tube being connected to a source of supply of one of the constituents of the combustion, and the other end opening into the said fuel inlet passage said recuperator tube having means therein for receiving heat by radiation from the tube and transferring such heat by convection to the fluid passing through the tube.

8. A furnace of the character described, adapted to operate upon combustible fuels, having a circular chamber therein, a refractory element positioned within said circular chamber and dividing said chamber into a work-receiving chamber and a surrounding combustion space, the said refractory element so separating the work-receiving chamber and the combustion space as to prevent products of combustion passing from the combustion space into the work receiving chamber, a fuel inlet passage within the furnace wall opening into the combustion space and a fuel outlet passage within the furnace wall connected to the combustion space, the said inlet and outlet passages being arranged in juxtaposition, whereby the products of combustion within the combustion space are caused to travel completely around the refractory wall enclosing the work-receiving chamber, a plurality of recuperator tubes within said outlet passage, a divided manifold associated with said tubes, the said tubes being alternately connected to opposite sides of said manifold, each of said tubes being connected to the said inlet pas-

sage, and means for introducing air and a combustible fuel to opposite sides of said divided manifold.

9. Heat transferring apparatus of the character described adapted to operate upon combustible fuel, comprising a work-receiving chamber, means for burning a fuel, and heat transferring elements interposed within the path of travel of the resulting products of combustion, said elements being adapted to receive heat by convection and transfer such received heat primarily by radiation, the number of said elements being progressively increased as the effective temperature of the products of combustion decreases.

10. A furnace for operating upon combustible fuels comprising a combustion space, a refractory wall within said combustion space defining and enclosing a work-receiving chamber, the construction being such that products of the combustion within the combustion space will not enter the work-receiving chamber, said refractory wall being positioned and constructed to receive heat energy on one side thereof from the products of combustion and transfer said received heat energy from the other side thereof into the work chamber largely by radiation, perforated members within the combustion space constructed and positioned for dividing the flowing products of combustion into fine streams and for effecting intimate contact between the flowing products of combustion and the surface of the perforated members to receive heat energy by direct transfer from the flowing products of combustion and to transfer said received heat energy primarily by radiation to the refractory wall.

11. A furnace for operating upon combustible fuels comprising a combustion space, a refractory wall within said combustion space defining and enclosing a work-receiving chamber, the construction being such that products of the combustion within the combustion space will not enter the work-receiving chamber, said refractory wall being positioned and constructed to receive heat energy on one side thereof from the products of combustion and transfer said received heat energy from the other side thereof into the work chamber largely by radiation, perforated members within the combustion space constructed and positioned for dividing the flowing products of combustion into fine streams and for effecting intimate contact between the flowing products of combustion and the surface of the perforated members to receive heat energy by direct transfer from the flowing products of combustion and to transfer said received heat energy primarily by radiation to the refractory wall, said perforated members being arranged in progressively increasing numbers as the temperature of the products

of combustion decreases to maintain the temperature of the refractory wall substantially uniform throughout its extent.

12. In a furnace of the character described a main cylindrical chamber, means for closing said chamber at both ends, a combustion space surrounding said chamber for the greater part of its length the opposite walls of the said chamber and said combustion space being substantially parallel, a tangential inlet for the heated products of combustion into the combustion space, an outlet from the said combustion space for the escape of the products of combustion, and a recuperator tube through which the fuel to be burned is passed on its way to the combustion space arranged with its outlet end opening into the said inlet, the construction being such that the combustible fuel introduced through said recuperator tube burns within the said inlet passage.

13. A furnace of the character described comprising a main cylindrical chamber, combustion space surrounding said chamber, means for preventing the products of the combustion within the combustion space from entering the cylindrical chamber, a fuel inlet passage opening into said combustion space, a preheating chamber above said combustion space, an outlet passage connecting the said combustion space and the preheating chamber, a plurality of recuperator tubes within said preheating chamber, and a divided manifold to which said recuperator tubes are connected.

14. A furnace of the character described comprising a work chamber, a combustion space surrounding said work chamber, means for preventing the products of the combustion within the combustion space from entering the work chamber, a fuel inlet passage opening into said combustion space, a preheating chamber above said combustion space, an outlet passage connecting the said combustion space and the preheating chamber, recuperator tubes positioned within said preheating chamber, and opening into the said inlet passage, and a burner element opening into the said inlet passage adjacent the ends of the recuperator tubes.

15. In a furnace of the character described a work chamber, a combustion space surrounding said work chamber, means for preventing the products of the combustion within the combustion space from entering the said work chamber, an inlet passage connected to the said combustion space, said passage intermediate its length being oppositely tapered, so that its effective area is progressively increased and then progressively decreased.

16. A furnace of the character described comprising a combustion space, a refractory wall within said combustion space defining and enclosing a work chamber, said wall

being so positioned as to also define a combustion passage completely surrounding the said refractory wall, said combustion passage being of progressively decreasing cross section throughout the greater part of its length.

17. A furnace of the character described comprising a chamber, a refractory wall positioned within said chamber defining and enclosing a work space within the said wall and a combustion space surrounding the said wall, a fuel inlet passage and an outlet passage connected to said combustion space, the said combustion space being of enlarged cross section area intermediate the point of fuel inlet and the point of exit of the burned gases.

18. A furnace for operating upon combustible fuels comprising a combustion space, a refractory wall within said combustion space defining and enclosing a work receiving chamber, the construction being such that products of the combustion within the combustion space will not enter the work-receiving chamber, said refractory wall being positioned and constructed to receive heat energy on one side thereof from the products of combustion and transfer said received heat energy from the other side thereof into the work chamber largely by radiation, and heat energy receiving means for maintaining the temperature of the refractory wall substantially uniform throughout its extent.

19. A furnace of the character described comprising a main cylindrical chamber, a combustion space surrounding said chamber, means for preventing the products of the combustion within the combustion space from entering the cylindrical chamber, a fuel inlet passage opening into said combustion space, a preheating chamber above said combustion space, an outlet passage connecting the said combustion space and the preheating chamber, a plurality of recuperator tubes within said preheating chamber, and a divided manifold to which said recuperator tubes are connected the said divided manifold and recuperator tubes being arranged with alternate tubes connected to the same side of the manifold.

20. In a furnace of the character described, comprising a work-receiving chamber, and means for heating said chamber, a closure door for said work-receiving chamber having a body of heat resisting material thereon, and means upon the surface of said body of heat resisting material for preventing the transfer of heat from said material when the door is in open position.

21. A furnace comprising a work space, means for heating the work space and the work therein, a closure member for said work space, and a layer of heat insulating material upon that portion of the closure member presented to the interior of the work

space for preventing loss of heat from the body of the closure member when said closure member is opened.

22. A furnace comprising a work space, means for heating said work space and the work therein, a closure member for said work space, the body of said closure member being composed of a refractory material, and a layer of heat insulating material upon that portion of the closure member which is presented to the interior of the work space for preventing the loss of heat from the bodies of the closure member when the closure member is opened and means for retaining said insulating material in place upon the body portion of said closure.

23. A furnace of the character described comprising a work space, means for heating the work space and the work therein, a closure member for said work space, and a layer of insulating material consisting of asbestos fibre or the like upon that portion of the closure member which is presented to the interior of the work space for preventing loss of heat from the body of the closure member when that closure member is opened.

24. A furnace of the character described comprising a work space having an opening thereto, means for heating said work space and the work therein, a swinging closure member for positioning within said opening, and means for supporting the closure member adapted for actuation to swing the closure into or out of said opening to open or close the work space, said means being so constructed that the inner face of the closure is at all times presented toward the work space as the closure is swung to open or closed position.

25. A furnace of the character described comprising a work space, a closure member for said work space, a rotatable rod mounted on the outer portion of said closure, an arm attached to said rod; a rotatable shaft carried by the furnace, a second shaft carried by the furnace, means on one of said shafts for causing rotation thereof, supporting means connecting such shaft and the said rod to support the closure, and controlling means connecting the other shaft and the arm on the said rod.

26. A furnace of the character described comprising a work space, a closure member for said work space, a rotatable rod mounted on the outer portion of said closure, an arm attached to said rod; a rotatable shaft carried by the furnace, a second shaft carried by the furnace, means on one of said shafts for causing rotation thereof, supporting means connecting such shaft and the said rod to support the closure, and controlling means connecting the other shaft and the arm on the said rod, and operating means tending to normally urge the closure toward

closed position and means for positively opening the closure against the action of said operating means.

27. A furnace of the character described comprising a work space, a closure member for said work space, a rotatable rod mounted on the outer portion of said closure, an arm attached to said rod; a rotatable shaft carried by the furnace, a second shaft carried 10 by the furnace, means on one of said shafts for causing rotation thereof, supporting means connecting such shaft and the said rod to support the closure, and controlling means connecting the other shaft and the 15 arm on the said rod, operating means for moving the closure toward open or closed position comprising a weight arranged to normally urge the closure toward closing position and a motor for positively opening 20 the closure against the action of said weight.

28. A furnace of the character described comprising a work chamber adapted to contain work to be heated, a refractory element associated with said work chamber, a combustion space, means for supplying a fuel to be burned within said combustion space and means for transferring heat energy from said heated products of combustion to the said refractory element the heat energy received by the said refractory element being 25 in turn transferred therefrom into the work, and means associated with said refractory elements for increasing the transfer of heat energy from the products of combustion into 30 the said refractory elements said means being of progressively increasing number as the 35 temperature of the products of combustion decrease, to maintain the refractory element at substantially uniform temperature 40 throughout its extent.

29. A furnace of the character described comprising a work chamber adapted to contain work to be heated, a refractory element associated with said work chamber, a combustion space, means for supplying a fuel 45 to be burned within said combustion space and means for transferring heat energy from said heated products of combustion to the said refractory element the heat energy received by the said refractory element being 50 in turn transferred therefrom into the work, a perforated body associated with said refractory element for receiving heat directly from the products of combustion flowing 55 through the said refractory element and transferring said received heat energy by radiation to the refractory element.

30. In a furnace of the character described, comprising a work-receiving chamber having an inlet opening therein, and means for heating said chamber; a closure door for said work-receiving chamber having means associated therewith for preventing the transfer of radiant energy through 60 the space between the door and the wall of 65 the inlet opening when the door is closed.

31. A furnace comprising a work space, means for heating the work space and the work therein, a closure member for said work space, and a layer of heat insulating 70 material upon the closure member and constructed to be presented to the interior of the work space for preventing loss of heat from the body of the closure member when said closure member is opened, said layer being 75 of small heat capacity.

In testimony whereof I hereto affix my signature.

HARRY F. SMITH
